HOUSING FOR A RADIO-PHONOGRAPH OR SIMILAR ARTICLE

Harvey K. McQuarrie and Michael D. Tate, Kitchener,
Ontario, Canada, assignors to Electrohome Limited,
Kitchener, Ontario, Canada

Filed Mar. 3, 1971, Ser. No. 120,785

Term of patent 14 years

Int. Cl. D14—03

U.S. Cl. D56—4

FIG. 1

FIG. 2

FIG. 4

FIG. 3

FIG. 1 is a side elevational view of a housing for a radio-phonograph or similar article, showing our new design, the appearance being substantially the same from all sides;

FIG. 2 is a top plan view;

FIG. 3 is a fragmentary cross-sectional view, partly in bottom plan, taken on line 3—3 in FIG. 1, the pedestal being omitted for convenience in illustration.

FIG. 4 is a fragmentary side and bottom perspective view, to an enlarged scale, the base of the pedestal being omitted for convenience in illustration.

The figures are shaded to indicate contrast in appearance.

We claim:

The ornamental design for a housing for a radio-phonograph or similar article, as shown and described.
